CLAIM

The ornamental design for a tire tread, as shown and
described.

DESCRIPTION

FIG. 1 is a perspective view of a tire tread showing our new
tread design, it being understood that the tread pattern is
repeated uniformly throughout the circumference of the tire
tread with the tread pattern being the same as for the side
shown; and,FIG. 2 is an enlarged fragmentary front elevation view of the
tire tread illustrated in FIG. 1 showing our new design.**1 Claim, 2 Drawing Sheets***Fig. 1*
